PLUMB BOB ADJUSTER

Ralph Elton Criswell, El Monte, Calif., assignor
of fifty per cent to Lewis B. Kingsley, Santa
Barbara, Calif.

Application July 15, 1952, Serial No. 298,960

2 Claims. (Cl. 33—217)

1

The present invention relates to line length adjusters in general and particularly to an adjuster for varying the effective length of a supporting cord or string for a plumb bob.

Plumb bobs are widely used in construction work by the builder, carpenter and by the surveyor. Conventionally the plumb bob is suspended by a string or cord from a support or plumb line above a selected point and at a height such that its lower pointed end is positioned immediately above that point. Upon being moved from one position to another, or upon changes in the height of the support, the length of the supporting cord must be changed in order to retain the plumb bob in its optimum relationship with respect to the point. Conventionally this is done by providing a suitable slip knot, which the worker ties after looping the cord over the supporting member. Such slip knots, however, have the undesirable characteristic of slipping and again of becoming so tight that a readjustment can be made only with difficulty. The delay following such developments is undesirable.

The adjuster constructed in accordance with the present invention is adapted to eliminate the undesirable factors characterizing the conventional slip knot adjustment. It comprises basically a reel upon which the cord or string can be wound and about which the unused length of string remains wound when the plumb bob is in use. Additionally it incorporates friction seating means through which the cord extends to the end that with the plumb bob supported above its point the effective length of the supporting cord can be readily varied simply by lifting the plumb bob and sliding the adjuster along the run of cord which passes through it. Upon the plumb bob again being released its weight causes the effective cord length to be fixed until a readjustment is made.

With an appreciation of the problems which characterize the use of plumb bobs it is an object of the present invention to provide a new and improved adjuster for readily effecting changes in the length of cord or string supporting a plumb bob. It is another object of the invention to provide a new and improved cord reel and adjuster for plumb bobs which is economically manufactured and which can serve as a storage unit for the cord when not in use. These and other more specific objects will appear upon reading the following specifications and claims and upon considering in connection therewith the attached drawing to which they relate.

Referring now to the drawing in which a pre-

2

ferred embodiment of the invention is illustrated:

Figure 1 comprises a view of a plumb bob supported by its own cord from a support and at a height determined by the position of the adjuster comprising the present invention, the entire unit being shown in a second adjusted position in phantom lines;

Figure 2 is an enlarged side elevational view of the adjuster per se;

Figure 3 is a view of the adjuster taken at right angles to the view of Figure 2;

Figure 4 is a transverse section upon the line 4—4 of Figure 2; and

Figure 5 is a second exemplification embodying a modified form of cord slot.

Referring again to the drawing, a plumb bob of conventional shape and size is illustrated and is indicated generally by the reference character 11. It comprises a conical body pointed at its lower end and formed at its upper enlarged end with a longitudinally extending neck portion 12 removably seating an interiorly threaded cap 13 in which one end of a cord 14 extends, being fixed therein as by having its end knotted. The cord 14 is adapted to support plumb bob 11 by extending upwardly and over a suitable support which in the drawing in Figure 1 is shown as a conventional hook 16. It is to be understood, however, that the support is not a part of the invention and may comprise a wire or a surveying instrument. The opposite end of the cord 14 is attached to the adjuster, indicated generally by the reference character 17, which, as illustrated in Figures 3 and 4, is H sectioned both transversely and longitudinally, being formed of parallel elongated sides 18 and 19 connected by a central elongated hub 21 of lesser length. As is seen clearly in Figures 2 and 4, the thickness and length of hub 21 is less than the length and width of side walls 18 and 19 so that a continuous channel is formed around the hub and between side plates 18 and 19. The adjuster body forms a suitable reel upon which the cord 14 can be wound. To secure the end of the cord hub 21 is formed with a transverse bore 22 through which the cord 14 is extended to be knotted at its end. That portion of the cord which is not required for the support of plumb bob 11 is simply wound on the adjuster or reel between the plates 18 and 19 and about the hub 21 in the manner clearly illustrated in Figures 2, 3 and 4.

Side plate 18 of adjuster 17 is formed at its opposite rounded ends with open ended slots 26 which lead into friction seats 27 comprising re-

cesses having offset ends extended towards the

adjacent end of the adjuster body. The slots 26 provide entrances or ways through which the cord can be slid into the seats 27.

For purposes of explanation the upwardly extending run of cord 14 from the adjuster will be identified by the reference character 14a and the return downward run by the reference character 14b. The cord from the hub 21 is taken out through the lower seat 27, along the outside of wall 18, back through the upper seat 27 to the interior of the adjuster, then up and over the support 16, then downwardly as the run 14b through the seat 27 from the interior of the adjuster to the exterior, down along the exterior of wall 18, in through the lower seat 27 to the interior of the adjuster, and finally directly downwardly to the plumb bob 11. The portion of run 14b between the upper and lower seats 27 is seen to be laterally displaced from its portions above and below the adjuster by the thickness of wall 18. Where it extends through the seats 27 it contacts the adjacent edges of the seats upon entering and leaving at points 28 and 29. The weight of the plumb bob 11 tends to straighten the run 14b causing the seats 27 effectively to exert a frictional resistance at points 28 and 29, as shown most clearly in Figure 3. That resistance is sufficient to bind the cord in place so that no slippage occurs and the length of the cord is fixed. Because of this friction clamping action the recesses 27 can properly be referred to as friction seats, for they effectively perform the function of frictionally clamping the cord run extended therethrough.

The exact shape and configuration of the seats 27 and of the slots 26 leading therein are not of the essence and, as shown in Figure 5, the slot, here indicated by the reference character 26a, may enter at a different angle into the seat 27a. The relationship in all forms is characterized in that the cord once positioned within the seats 27 and drawn taut by the weight of the plumb bob is fractionally held against sliding action until the weight of the plumb bob is withdrawn to remove tautness whereupon the adjuster is freely slideable along the run 14b.

To adjust the length of the supporting cord 14 to effect a variation in the height of the plumb bob 11, let us say from the full line position of Figure 1 to the dotted line position, it is only necessary to lift the plumb bob 11 whereupon the binding action present in the seats 27 is removed and the adjuster 17 can be slid upwardly along the cord from the full line position to the dotted line position of Figure 1. This effectively increases the length of the cord and the plumb bob moves from the full to the dotted line position in the same figure. To shorten the effective length of the cord the adjuster is moved along the run 14b in the opposite direction.

While the particular apparatus herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

10 I claim:

15 1. In a plumb bob unit a plumb bob, a cord connected at one end to said plumb bob, an adjuster to which the opposite end of said cord is connected, said adjuster comprising a reel having spaced parallel side walls and a central hub about which said cord is wound, one of said side walls including spaced friction seats through which said cord extends, each of said seats being formed with a slot through which said cord can be fed, said seats being arranged so that a vertical run of said cord can pass from the interior of said reel to its exterior and then, after extending vertically down along the exterior of said reel, can pass from the exterior into the interior of said reel, the extensions of the cord above and below said reel being displaced from the extension along the exterior of said reel by the thickness of said one side wall, said adjuster being slideable along said cord to vary the length of said cord upon the weight of said plumb bob tending to move said extensions into alignment being withdrawn.

20 2. An adjuster for plumb bob cords, which comprises a reel formed with a pair of corresponding spaced parallel side walls and a connecting central hub of lesser dimensions, said side walls forming a channel adapted to receive a plumb bob cord wound around said hub, one of said side walls having substantial thickness and being formed at opposite sides of said hub with aligned cord seats to direct a cord run from the exterior to the interior of said reel and vice versa, each of said seats being formed with a connecting open-ended slot through which a cord run can be advanced into said seat, each of said seats being also formed with relatively adjacent outer and inner edges which are offset the thickness of said one side wall to provide a binding action with said cord.
